C. W. Durbrow, both of San Francisco, Calif.

Application October 11, 1937, Serial No. 168,405

5 Claims. (Cl. 95—75)

My invention relates to an apparatus for printing on photographic film, and particularly to means for providing suitable illumination at the printing aperture; and it has an especially valuable application in the printing of film employed in the making of colored motion pictures.

An object of my invention is to provide a printer for photographic film in which the intensity of illumination at the printing aperture is accurately controllable. Another object is to provide a printer for motion picture film in which the light at the printing aperture may always be of substantially the same color regardless of the intensity to which it is adjusted.

Another object is to provide a printer suitable for simultaneously printing through two negatives onto opposite sides of a motion picture film comprising one or more emulsions.

Another object of the invention is to provide in a printer for motion picture film means for quickly and accurately changing the intensity of illumination at the printing aperture to a predetermined value.

Another object is to provide in a printer means for continuously indicating the luminous intensity of the source of illumination of the printing aperture.

A further object of my invention is to provide means in a printer to prevent the accidental exposure of the film during the threading of the printer.

These and other apparent objects I attain in a manner which will be clear from a consideration of the following description taken in connection with the accompanying drawings, of which:

Fig. 1 is a view of the front of my printer.

Fig. 2 is a view of the back of my printer.

Fig. 3 is a cross-sectional view of the printer taken along the line 3—3 of Fig. 4 in the direction of the arrows as shown.

Fig. 4 is a cross-sectional view of the printer taken along the line 4—4 of Fig. 3 in the direction of the arrows as shown.

Fig. 5 is a view from the front of the printer of the mechanism controlling the printing illumination, with the disc in front partially cut away.

Fig. 6 is a cross-sectional view of the mechanism of Fig. 5 taken along the line 6—6.

Fig. 7 is a cross-sectional view of a portion of the mechanism shown in Fig. 6 taken along the line 7—7, with the rear of the ratchet casing partially cut away.

Fig. 8 is a view of one element of the mechanism of Fig. 6.

Fig. 9 is a view of another element of the mechanism of Fig. 6.

Fig. 10 is a view of a metering spacer employed in the mechanism of Fig. 6. 5

Fig. 11 is a view in cross-section through a portion of the printer taken along the line 11—11 of Fig. 1 in the direction of the arrows as shown.

Fig. 12 is a view of the contacting device employed in connection with the light change mechanism. 10

Fig. 13 is a view of a portion of the printer taken along the line 13—13 in Fig. 3 at the face of the pressure plate in the direction of the arrows as shown. 15

Fig. 14 is a view of the lower half of the contacting device of Fig. 12 showing a notched negative passing through the device.

Fig. 15 is a cross-sectional view of a portion 20 of the printer taken along the line 15—15 of Fig. 1 in the direction of the arrows as shown.

In the printing of photographic film and particularly motion picture film in which high standards of quality obtain, it is necessary to provide 25 illumination which is dependent upon the density of the negative through which the light must pass to expose the positive being printed. In the printing of motion picture film it is desirable that the intensity of illumination at the 30 printing aperture be very accurately adjusted to the proper value. This is true because in motion pictures one scene follows another and if there were serious differences in density of the photographic image between successive scenes 35 it would be extremely unpleasant and the artistic effect of the picture would be largely lost. In the making of modern motion pictures with a sound track photographically reproduced on the positive film, the development of the positive 40 is definitely fixed by the requirements of the sound track, and the density of the positive film is then determined practically entirely by the intensity of the illumination employed in printing, assuming the positive emulsion and negative density to be given. 45

The accuracy with which the intensity of illumination in printing must be fixed is greater in the printing of positive film to be employed in the making of colored motion pictures, for 50 not only must the overall density of the picture be considered but the density of the two or more separately colored images must be balanced, or the resulting color of the complete colored film will not be true. 55

Heretofore it has been customary to change the intensity of illumination at the aperture of a printer by changing the electrical resistance in series with the electric lamp serving as the source of illumination. This change has generally been produced by means of a light change device comprising a large number of electrical resistance units and various contacts by which any chosen resistance might be inserted in the circuit. Generally the device is set up, prior to the printing of a film involving many scenes, with a separate resistance, determined by the requirements of each scene, ready to be automatically inserted into the lamp circuit when the corresponding scene reaches the printing aperture. It is obvious that such an arrangement contains many contacts, every one of which must function with no resistance of its own if the predetermined circuit resistance is to be secured. Actually, it is found that these contacts do not perform perfectly; in fact they are a constant source of trouble and require continual servicing. These devices present other difficulties also. As they heat, their resistance changes, resulting in further variation of the illumination. Then, a major objection to the resistance method of changing illumination is that as the current through the lamp is reduced the color of the light emitted also changes along with the intensity. This not only results in effective exposures of the film being affected because of the dependence of film sensitivity upon color, but also results in different contrasts in the various scenes because, for the same development, the contrast is dependent upon the color of light used in exposure. The latter effect is important in high quality color processes in which variations in contrast may disturb the color balance.

In the printer of my invention I provide means for continuously indicating the luminous intensity of the illumination sources to insure against their deterioration or sudden failure going unnoticed, and I vary the intensity of illumination at the aperture by interrupting the light from the illumination source in different degrees, depending upon the illumination required. Thus, the luminous intensity and color of the source remain substantially constant; and since no resistances, contacts, etc., are employed, a prominent source of trouble in commonly used devices is avoided.

The embodiment of my invention illustrated in the drawings is a printer adapted to simultaneously print through two negatives onto a positive film interposed between the two negatives. This printer is particularly useful in printing color films in which case one negative may be that which has recorded the predominantly green or blue portion of the photographed scene and which for convenience will hereinafter be referred to as the green negative, and the other negative may be that which has recorded the predominantly red portion of the scene and which will hereinafter be referred to as the red negative. Between these negatives is interposed at the printing aperture a positive film which may be of duplitzed character, i. e., one which has a sensitive emulsion on each side of the supporting base or it may comprise simply a supporting base with one or more emulsions on one side thereof.

In the drawings, referring particularly to Figs. 1 and 2, the frame of the printer is designated by numeral 20. Carried by the frame 20 is a panel 21 supporting the various reels on which

the film is carried. Raw positive film stock is carried on the reel 22 and after passing through the printer is taken up on reel 23. The green negative is carried on reel 24 and is, after passing through the printer, taken up on reel 25. The red negative is carried on reel 26 and is, after passing through the printer, taken up on reel 27. The sound negative is carried on reel 28 and is after passing through the sound track printing aperture, taken up on reel 29. In the operation of the printer, the raw positive stock 30 first passes together with the sound negative 31 past the sound track printing aperture, which together with the drive sprocket, gate, illumination means, etc., is generally designated by the numeral 32. The sound negative is then wound up on reel 29 and the raw stock 33 continues on to the picture printing aperture. Before it arrives at the aperture it is met on one side by the green negative 33 and on the other side by the red negative 34 and the three films pass over and are driven together by the drive sprocket 35. Forming a loop 36, the three films next pass to the light change contacting device 37 which initiates the change of illumination of the printing aperture in response to an interruption in the film edge located at a change of scenes, as will hereinafter be explained in detail. The red negative only passes through the contacting device 37, the green negative and the raw stock passing over the top thereof. Thence the three films are intermittently drawn past the picture printing aperture 38 by means which will hereinafter be described in detail, pass over the driving sprocket 39, through the positively driven sprocket mechanism 40, and separate to pass to their respective take-up reels. At the printing aperture one side of the positive film is exposed through the green negative by light which comes from a lamp within the lamp-house 41, and the other side of the positive film is simultaneously exposed through the red negative by light which comes from a lamp within the lamp-house 42. The illuminations on the two sides at the aperture due to the two lamps are very accurately controllable in a manner which will hereinafter be described in detail.

The mechanism by which the sprockets and take-up reels are driven is best illustrated in Figs. 2, 11, and 15 and is as follows. The electric motor 45, which is preferably a substantially constant speed motor, is mounted on the frame by means of bracket 46 and provides the motive power for the printer. The shaft of the motor is connected through spur gears 47 and 48 with a horizontal shaft 49 journaled in the frame and carrying the flywheel 50. In geared connection with the shaft 49 is a vertical shaft 51 geared to the shaft 52 of sprocket 35, and geared to shaft 52 is also the vertical shaft 53 which is in geared connection with the shaft 54 on which is carried the sprocket 55 which drives the film at constant velocity past the sound printing aperture 56. The shaft 54 also carries a flywheel 57 and pulley 58 which drives the sound negative take-up reel 29 through belt 59. In geared relation to the shaft 49 is also vertical shaft 60 which is geared to another vertical shaft 61 which in turn is geared to the various sprockets of mechanism 40 and also to the pulley shaft 62 carrying pulleys which drive the take-up reels 23, 25, and 27 through belts 63, 64, and 65.

The three films 33, 30 and 34 are moved intermittently past the picture printing aperture by a mechanism which causes two claws to move

substantially horizontally with respect to the film, into perforations at opposite edges of the films and move vertically downward relative to the printing aperture until the films are in position for printing, whereupon the claws are withdrawn from the perforations substantially horizontally and moved vertically upward to be in position to again engage the film after an exposure has been completed. Referring particularly to Figs. 3, 4, and 15, it will be seen that on the horizontal shaft 49 is a heart-shaped cam 68 engaged by a partially rectangular follower 69 which carries a structure 70 vertically up and down when the cam 68 is rotated. Mounted on structure 70 and movable horizontally to and from the films are two claws 71 and 72 whose ends are adapted to engage perforations at opposite edges of the films to move them. The ends of the claws are preferably so shaped that one claw fully fits the perforations, while the other claw fits the perforations in a direction longitudinal of the film only. By the use of claws of this shape the three films are accurately registered with respect to one another before the claws are removed, which is very essential in producing good colored pictures, yet shrinkage of the film is permitted by reason of one claw fitting only in the longitudinal direction. The claws 71 and 72 are moved into and out of the film perforations by the elongated pinions 73 and 74, respectively, which are meshed with racks constituting the outer sides of the claws. The pinions 73 and 74 are journaled on the frame and are rotated by engagement of eccentric pins 75 and 76 with peripheral grooves 77 and 78 in the cylinders 79 and 80. The grooves 77 and 78 are so shaped and oriented that while the follower 69 is at the top of its stroke, the pinions 73 and 74 are rotated to cause the claws 71 and 72 to be inserted in the perforations; and while the follower 69 is traveling downward the pinions 73 and 74 are stationary. When the follower 69 is at the bottom of its stroke, the pinions 73 and 74 are rotated so as to withdraw the claws 71 and 72; and while the follower 69 is moving vertically upward, the pinions are again stationary. By use of this mechanism, the film engaging claws are moved in a substantially rectangular orbit, and the films are brought to rest vertically before the claws are withdrawn. For this reason accurate vertical registration of the three films is secured without the necessity of registration pins being present in the perforations at the time of exposure.

At the picture printing aperture 38 is a plate 83 against which the red negative bears. As may best be seen in Figs. 3, 4, and 11, this plate, together with its supporting structure, and the light tunnel 84, shutter housing 85, lamp-house 42, and connected parts are pivoted on the pivot 86, mounted on the frame, and may be dropped down to permit threading of the printer. On the opposite side of the three films and resiliently bearing on green negative 33 adjacent the aperture is the pressure plate 87 which insures positive contact between the three films during exposure. During movement of the films past the aperture, the pressure plate is backed away by means of four pins 88 which pass through holes in plate 83 and engage the face of the pressure plate 87 beyond the edges of the film. The pins 88 are carried on two strips 89 which at their mid-points are pivotally mounted on a bifurcated lever 90 pivoting about a fulcrum at 91 on the supporting structure 92 for the plate

83. The upper end of lever 90 carries an arm 93 ending in a cam follower 94. This cam follower 94 rides on a peripheral cam 95 cut on the cylinder 80, seen in Fig. 13, and the cam 95 is so shaped that when the film is about to be moved the lever 90 is rotated sufficiently to cause the pins 88 to be pressed against the pressure plate 87, so as to relieve the pressure on the film, and after the film has come to rest, the pins 88 are withdrawn, allowing the pressure plate to again press against the films. To permit the threading of the printer without interference from the pressure plate, I provide two projections 96 and 97 attached to the pressure plate 87 and extending back therefrom, and having ends turned into directions parallel with the pressure plate as seen in Figs. 3 and 15. I also provide rods 98 and 99 slideable in the frame and having bevelled ends 100 and 101 adapted to engage the inner faces of the right-angularly turned ends of projections 96 and 97 and pull the pressure plate away from the film. The rods 98 and 99 are connected by member 102 which is moved by a pin 103 slideably engaged by the lever 104 pivoted about the pivot 105. Raising the handle portion of the lever 104 causes the pressure plate to be retracted.

Exposure of the emulsion of the positive stock adjacent the red negative 34 takes place through the red negative by reason of light from the electric lamp 110 mounted in the lamp-house 42. As seen in Figs. 3 and 4, the light passes through an opening 111, through a light change device generally indicated by numeral 112, hereinafter described in detail, through the opening 113 in shutter 114, and through the light tunnel 84, to the films. Exposure of the emulsion of the positive stock adjacent the green negative 33 takes place through the green negative by reason of light from the electric lamp 116 in lamp-house 41. The light from lamp 116 passes through the opening 117, through the light change device 118, similar to the device 112, through the opening 119 in shutter 120 and through the light tunnel 121, to the films. In this case the light tunnel 121 is partly formed by the hollow structure 79 supporting the film moving claws. Hence this portion 70 enclosing part of the light tunnel reciprocates vertically which explains the necessity for its being vertically elongated, as best shown in Fig. 3. In order to improve the uniformity of illumination at the films I may provide frosted glass diffusing plates 122 and 123 in the paths of light from the two lamps, or I may employ in these positions filter plates to enable printing to be done with any selected colors of light. The shutters 114 and 120 are thin discs having arcuately disposed openings 113 and 119, respectively, adapted to uncover the respective sources of light. The shutters are mounted to be turned by the same shaft 124 and are driven continuously by means of the geared connection 125 with the shaft 60. The openings 113 and 119 are so positioned that they uncover the respective sources 110 and 116 when the films are in position for exposures to be made. Since the shutter housing 85 must move with the plate 83 and the attached structure to permit the films to be threaded, I provide a break in the shutter shaft near shutter 114 at 126, the two ends of the shaft at the point of disconnection having surfaces that lock with one another in one position to provide a driving connection when the shutter is in operative position. A spring 127 assures continuous engagement of 75

the connection 126 while the shutter is in operative position. The lamp 110 is in series with rheostat 128, and the lamp 116 is in series with the rheostat 129, each of these circuits being connected to a source of electricity which is preferably accurately controlled in voltage. By variation of the rheostats 128 and 129 the luminous intensity of the respective lamps may be adjusted to the desired values.

In order to assure constancy of the sources of light 110 and 116 I provide means for continuously indicating the luminous intensity of the lamps. Attached to the lamp-houses 42 and 41 and connected to the interiors thereof by openings 132 and 133 respectively, are cases 130 and 131, respectively, containing matched light-measuring cells 134 and 135, respectively. While other types of light sensitive cells may be employed, I prefer to employ cells of a photo-voltaic type such as that known as the Photronic cell, for these cells generate their own electromotive force in response to light and are stable and of relatively long life. The cell 134 is electrically connected to the indicating meter 136 and the cell 135 is connected in circuit with the meter 137. By this means, the indications of meters 136 and 137 are a measure of the amounts of light falling upon the respective cells 134 and 135, which is turn are proportional to the luminous intensities of the respective sources 110 and 116. Thus, in my printer, it is impossible for a lamp to gradually lose intensity or suddenly fail without this change being indicated. This device makes possible the accurate balancing of illumination on the red and green negative and permits this balance to be continuously maintained.

An important feature of my invention is the means by which I change the illumination at the aperture from scene to scene of the picture being printed. In the path of the light from lamp 116, in front of opening 17 are two adjacent relatively movable plates 140 and 141 both preferably mounted slidably in the frame, as shown in Figs. 4, 5, 6, 8 and 9. Each of these plates has one or more apertures preferably comprising one or more spaced parallel slits 142 opposite the opening through which light passes to the films. The slits 142 are preferably made .025 inch in width and the distance between adjacent edges of any two slits is preferably made .021 inch. Thus, if the two plates are placed against one another with their slits 142 parallel and if they are then positioned so that the slits perfectly register with one another the maximum amount of light will pass through, there being openings of .025 inch; while if the plates are slid one along the other to the point where the opaque portions of plate 141 are entirely overlying the transparent portions of plate 140, there will be only .025-.021=.004 inch openings available for transmission of light and illumination on the film will be reduced to the minimum possible with this combination of slits. If the relative lateral positions of the two plates 140 and 141 are progressively changed between these two limits a smooth variation in the intensity of illumination on the printing aperture is obtained. I preferably provide means for varying these positions in 21 steps providing 22 intensities of illumination.

This variation is accomplished by providing on the plate 140 a jaw 143 in the plane of plate 141 and providing spacers of measured thickness adapted to enter between the jaw 143 and the similar jaw 144 constituting the end of plate 141.

A spacer 145 is fixed to the plate 140 in the plane of plate 141 and serves to always maintain a spacing between the jaws 143 and 144 which will permit the easy entrance of the metering spacers therebetween. A pin 168 is fixed in plate 140 and another pin 169 is fixed in plate 141 and adapted to pass through hole 170 in plate 140. A spring 171, seen in Fig. 4, is attached at opposite ends to pins 168 and 169 and acts to draw the jaws 143 and 144 together in contact with the metering spacers. The metering spacers 146 are preferably cylindrical plugs, like that shown in Fig. 10, the upper portion 147 of which is smooth and accurately of a certain diameter corresponding to a numeral which is for convenience marked on the top. The lower portions of the spacers 146 are of uniform size and are split to be retained by friction in holes provided for that purpose. A rotary member in the shape of a disc 148 is mounted on the shaft 149 so that it rotates with its periphery just out of contact with the jaws 143 and 144, as shown in Figs. 5 and 6. In the periphery of the disc 148 are a large number of uniformly spaced holes 150 into which the metering spacers 146 are adapted to be inserted and retained by friction. When the spacers 146 are so inserted in the disc 148, and the disc is intermittently rotated, the spacers successively space the jaws apart distances which correspond to the diameters of the respective spacers 146. As each spacer 146 comes between the jaws 143 and 144, then, the slits 142 of the plates 140 and 141 are laterally adjusted relative to one another so as to change the aperture area common to both plates and thus to let more or less light through, depending upon the diameter of the particular spacer. It will be observed that since both plates 140 and 141 are made movable, their relative lateral positions depend only upon the thickness of the spacers 146 and are not affected by any misalignment or lateral shifting of disc 148.

The disc 148 is designed to be retained stationary with one of the spacers between the jaws until it is desired to change illumination when, in response to an electric current, the disc is caused to be rapidly rotated to bring the next spacer between the jaws. The disc 148, rotatably mounted on shaft 149, is retained on the shaft by the knurled nut 151 and is connected for rotation with the ratchet wheel 152 by the pin 153 carried by the wheel and extending into a hole in the disc 148. The ratchet wheel 152 is provided with peripheral teeth 154 which are engaged by a pawl 155. Back of the ratchet wheel and in a recess in the frame is a spiral coil spring 156 which is attached at 157 to the shaft 149 and at the other end to the ratchet wheel at 158, seen in Fig. 7. The action of the spring is to tend to cause rotation of the disc 148 in the direction shown by the arrow in Fig. 5. The shaft 149 is restrained from turning in the frame by clamping it by means of screw 159. The heel 160 of the pawl 155 is normally held in engagement with one of the teeth of the ratchet 152 by means of the spring 161 so as to prevent rotation of the ratchet, and the pawl is so located that it stops the disc 148 in such a position that one of the spacers 146 is between the jaws 143 and 144. The pawl 155 is mounted on the short shaft 162 which passes through the adjacent frame and is turned by arm 163 whose end is acted upon by a yoke 164 on the plunger 165 of an electromagnet 166, as shown best in Fig. 7. Upon energizing the coil of the electro-

magnet 166, the plunger is drawn in, swinging the arm 163 down, lifting the heel 160 of pawl 155 out of engagement with the ratchet and tipping the toe 167 of the pawl into engagement with the ratchet so as to limit the rotation of disc 148, which promptly ensues, to only slightly more than sufficient to permit the heel of the pawl to avoid the tooth with which it has been in contact, when next the heel engages the ratchet. When, now, the current through the electromagnet coil is broken, the pawl 155 will rotate so as to cause toe 167 to lift and heel 160 to drop into engagement with the ratchet, whereupon the disc 148 will rotate slightly until heel 160 stops the disc by engagement with the tooth of ratchet 152 which is immediately next to the one previously engaged. Thus, by momentarily making and breaking the circuit of the electromagnet coil, the disc 148 is rotated by one step to bring a new spacer 146 between the jaws 143 and 144. To limit the rotation of the disc to one revolution, I provide an annular groove 133 in the back of ratchet wheel 152 which is not quite a complete circle. Into the groove 133 projects a screw 139 which is secured in the wall of the ratchet casing. The ends of groove 133 are adapted to engage the screw 139 in the first and last operative positions of the disc 148.

In the printing of motion pictures including a plurality of successive scenes, the intensity of illumination at the printing aperture may be changed from one scene to the next to take account of varying negative density by inserting suitable metering spaces 146 successively around the disc 148 and causing the disc to be advanced one step each time one scene changes to the next. This change is ordinarily initiated by the passage past a contacting device 37 of a notch 172 in the edge of the negative film located near the point of change from one scene to the next. In my printer I prefer, when printing from two negatives, to notch only the red negative and pass it alone through the device 37. The contacting device 37 is illustrated in Figs. 12 and 14 and may comprise a plate 173 having a track 174 on which the film 34 slides, the plate being undercut in the picture area, and being provided with a hinged gate 175 with a catch 176 which confines the red negative film in a plane during the passage through the device. The positive stock and the green negative pass over the contacting device on the track 184. Beneath the plate 173 and confined in a recess thereof by insulating cover 177 is a sliding member 178 continuously urged by spring 179 toward the notched edge of film 34. The member 178 has mounted near its end adjacent the notched edge of film 34 a rotatable roller 180 which is adapted to engage the edge of the film 34 and momentarily move to the left and back (Fig. 12) when a notch 172 passes by. The sliding member 178 carries at its other end a downward projection 183 of insulating material which is adapted to engage contact 181 and move it into contact with contact 182 when roller 180 enters notch 172.

Normally, when the roller 180 is riding on the edge of film 34, the contacts 181 and 182 are separated. The contacts 181 and 182 are connected in series with a source of electric current and the coil of electromagnet 166. When, therefore, a change of scene occurs and a notch 172 passes the roller 180 the contact 181—182 is made and current momentarily passes through the coil of the electromagnet 166. The disc 148 is moved by one step and a new metering spacer

146 comes between the jaws 143 and 144 to effect a relative positioning of the slits 142 of plates 140 and 141 which allows light to pass in an intensity determined by the diameter of the spacer 146 which was inserted in the particular position of disc 148 which is now effective. In this manner a large number of scenes may successively be printed, each with its own suitable illumination intensity, the number of scenes being only limited by the number of holes available for spacers 146.

The light change device 112 employed to change the illumination at the aperture coming from lamp 110 is similar and is operated similarly to the light change device 118 just described.

In order to provide against accidental exposure of the positive stock by swinging down the light tunnel 84, lamp-house 42, and associated parts, I provide special means now to be described.

As seen in Figs. 4 and 6, adjacent to the light change device 118 and between it and the housing for shutter 120 is a slidable plate 190 having a handle 191 attached thereto. In the plate 190 is a ruby glass window 192 which is so located as to cover the slits in light change device 118 and permit the transmission of only red light to the light tunnel 121 when the plate 190 is pulled outwardly to its extreme position. Projecting into a slot 193 in plate 190 is the handle of a toggle-type electric switch 194, the slot being so located that when the plate is pulled outwardly the switch is operated to break the connected circuit. The switch 194 is connected in circuit with the lamp 110. The result, then, of pulling the handle 191 together with its attached plate 190 outwardly to the extreme position is to eliminate entirely any light from lamp 110 and to permit only red light to pass to the aperture to aid in threading the printer. The lamp-house 42, light tunnel 84, and associated parts can only be swung down around pivot 86 if the handle 191 is pulled out to its extreme position in which all white light is prevented from coming from the printer.

The house 42 and associated parts are locked in operative position by the end of lever 195 which is held under the large head of a screw 196 in the frame, as seen in Fig. 11. The lever 195 pivots about the pivot 197, and at its end engages a substantially horizontal arm 198 pivoted at 199 on the frame and urged downwardly by spring 200.

The lever 195 is prevented from moving to the unlocked position by the slidable bar 203 which engages the under side of the locking end of the lever. Slidably engaging in a slot thereof a pin fixed in plate 190 is a lever 204 pivoted at 205, as shown in Fig. 4, the end of which lever resides between pins 206 on bar 203 and causes the bar to be moved toward the right in Fig. 11 when the handle 191 is pulled out. Thus, when the handle 191 is pulled outwardly to its extreme position, the bar 203 is removed from beneath the lever 195, permitting the latch to be unlocked. In this position of the bar 203, the foot 202 of pawl 201 falls into the notch 207 in the upper side of bar 203 and prevents the bar 203 from being slid back to the left until the lever 195 is brought into the locked position.

As the end of lever 195 is brought up into the locked position, it engages the end of arm 198 and a finger-like projection 208 on the under side of the arm 198 hooks the pawl 201 raising its foot out of notch 207, whereupon the handle 191 can again be pushed in to cause both sides of the printing aperture to be illuminated. It will be observed that this means

I make it impossible for any light to come from the lamp 110, or white light to come from the lamp 116, when the light tunnel 84, lamp-house 42, and associated parts are swung down out of 5 operative position.

It is understood that the various mechanisms herein employed in connection with a printer for printing opposite sides of a color film, such as my means for accurately indicating and for 10 changing printing illumination, my means for preventing accidental exposure of the film, etc., may equally well be applied to a printer making a single exposure. And various changes and 15 modifications in design and construction from the embodiment illustrated herein may also be made by those skilled in the art without departing from the spirit of the invention defined by the appended claims.

I claim as my invention:

20 1. In a printer for photographic film including a source of light for illuminating said film, two adjacent members relatively movable in a direction transversely of the path of light illuminating said film and each apertured in said path, said 25 two members having opposing surfaces which are arranged normal to the direction of their relative movement and which are adapted to be spaced apart predetermined distances by metering spacers, resilient means urging said opposing surfaces 30 toward each other, a movable spacer supporting member carrying a plurality of removable metering spacers adapted upon movement of said spacer supporting member to successively enter between said opposing surfaces, a spring drive tending to 35 produce movement of said spacer supporting member, a ratchet connected for movement with said spacer supporting member, a pawl engaging said ratchet, and means for operating said pawl to permit movement of said spacer supporting 40 member a distance required to introduce a different metering spacer between said opposing surfaces.

2. In a printer for motion picture film including means for moving film through the printer and a 45 source of light for illuminating said film, two adjacent members relatively movable in a direction transversely of the path of light illuminating said film and each apertured in said path, said two members having opposing surfaces which are arranged normal to the direction of their relative 50 movement and which are adapted to be spaced apart predetermined distances by metering spacers, resilient means urging said opposing surfaces toward each other, a rotary member carrying a 55 plurality of removable metering spacers adapted upon rotation of said rotary member to successively enter between said opposing surfaces, a spring drive tending to produce rotation of said rotary member, a ratchet connected for rotation 60 with said rotary member, a pawl engaging said ratchet, an electromagnet for operating said pawl to permit rotation of said rotary member through

an angle required to introduce a different metering spacer between said opposing surfaces, and means to momentarily energize the coil of said electromagnet to effect operation of said pawl in response to an irregularity in the passing film. 5

3. In a printer for motion picture film including means for moving films through the printer and a source of light for illuminating said film, two adjacent plates relatively movable in a lateral direction and each having a plurality of parallel 10 slits therein in the path of light illuminating said film, the slits of one of said members being adapted to transmit light passed by the slits of the other of said members, opposing parts of said two members forming jaws adapted to be laterally 15 spaced apart predetermined distances by metering spacers, a spring urging said jaws together, a spacer limiting the nearness of said jaws, a rotary disc carrying on its periphery a plurality of removable metering spacers adapted upon rotation of 20 said disc to successively enter between said jaws, a spring tending to produce rotation of said disc, a ratchet connected for rotation with said disc, a pawl engaging said ratchet, an electromagnet for operating said pawl to permit rotation of said disc 25 through an angle required to introduce a different metering spacer between said jaws, and means to momentarily energize the coil of said electromagnet to effect operation of said pawl in response to an irregularity in the passing film. 30

4. In a printer for photographic film including a source of light for illuminating said film, two adjacent members relatively movable in a lateral direction and each apertured in the path of the light illuminating said film, a rotary member 35 carrying on its periphery a plurality of removable radially extending spacers, a pair of jaws adapted to engage opposite sides of one of said spacers and connected to said members for control of the relative lateral position of said members, and means for intermittently rotating said rotary member to successively bring said spacers between said jaws. 40

5. In a printer for photographic film including a source of light for illuminating said film, two adjacent members relatively movable in a lateral 45 direction and each having a plurality of parallel slits therein in the path of light illuminating said film, the slits of one of said members being adapted to transmit light passed by the slits of the other of said members, a rotary member having radial recesses in its periphery, a plurality of radially extending pins frictionally retained in said recesses, a pair of jaws adapted to engage opposite sides of one of said pins and connected to said members for control of the relative lateral 50 position of said members whereby the light passing through said members is determined by the thickness of said pin, and means for intermittently rotating said rotary member to successively bring said pins between said jaws. 60

CHARLES F. JONES.
